O. R. ERWIN

FIRE EXTINGUISHING APPARATUS

Original Filed Dec. 20, 1920

Inventor
Orlando R. Erwin,
By his Attorneys
Meyers, Cavanaugh & Hyde

Patented Dec. 28, 1926.

UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

FIRE-EXTINGUISHING APPARATUS.

Application filed December 20, 1920, Serial No. 431,924. Renewed November 13, 1923.

- This invention relates to fire extinguishing apparatus, and more particularly to a fire extinguishing apparatus of the type in which component chemical solutions are commixed in the event of fire for the production of a fire extinguishing medium such as foam; and has special reference to the provision of an apparatus of this type designed especially for the protection of isolated fire hazards and embodying the improvements disclosed and claimed in my copending application to a method and apparatus for extinguishing fires, Serial No. 421,634, filed November 4, 1920.
- A principal object of the present invention comprehends the provision of a fire extinguishing system of the foam producing type in which foam may be generated and delivered to relatively high elevations without the employment of auxiliary operating mechanism for the system, the system being thus adapted for the protection of isolated localities such as segregated or separated oil tanks.
- In systems of the foam producing type for the protection of oil tanks or the like, it has been the custom to provide means for placing the chemical component solutions under pressure either by the provision of a chamber containing air under pressure, or by the provision of a pumping system associated with the tanks containing the solutions in order to obtain sufficient force to raise the solutions and the generated foam to high elevations such as to the top of an oil tank, which in many instances may measure as high as 30 feet. One of the problems in connection with the extinguishing of fires of this nature has been the protection of isolated tanks for small properties where the cost of a pumping system is prohibitive. I have discovered, as disclosed in my above-mentioned copending application, that the foam compound may be delivered to the top of the oil tanks without the employment of pumping means or other auxiliary apparatus of this nature, and more specifically that the production and delivery of the foam may be effected by arranging the parts of the apparatus in such a manner that the solutions are fed by a substantial gravity head into a mixing chamber, and there commixed for the production of the foam and the foam delivered to the high elevations by the difference in specific gravities between the component solutions and the resulting foam, and the present invention has for its main object the provision of an improved system of this nature.
- A further principal object of the present invention relates to the provision of a system of the nature above referred to in which the parts are co-ordinated to provide an apparatus automatically operated upon the occurrence of the fire. In accomplishing this object of the invention, the tanks containing the component solutions are connected to a mixing chamber by means of solution lines which are normally closed and are maintained dry, means being provided for opening the said lines upon the occurrence of a fire, such means including a control line connected to the solution tanks and adapted to be operated upon the occurrence of a fire adjacent the region to be protected. To insure a simplicity of construction and to obtain dependability of operation, a coordinate object of the invention includes the provision of means forming part of the system for enclosing or housing the control line to maintain the integrity of the same.
- A still further object of the present invention relates to the provision of an apparatus of the nature referred to in which the parts are arranged to provide for a non-freezing system.
- A still other and ancillary object of the invention includes the production of an apparatus of the nature referred to in which the means for opening the solution lines in time of fire may be operated manually from a point remote from the fire in addition to the operation thereof automatically from a point adjacent the fire.
- To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which—
- Figure 1 is a side elevational view of the apparatus with parts shown in cross section to disclose the interior construction of the same.
- Figure 2 is a front elevational view of one of the tanks with its associated parts, and
- Figure 3 is a plan view of the solution

tanks showing the piping connection thereto.

Referring to the drawings, the solution tanks 5 and 6 are adapted for the reception of the acid and basic solution respectively, having compositions described, for example, in the patent to Walker, Number 1,186,248 of June 6, 1916. Associated with the solution tanks is a mixing chamber 7, located in the bottom of a pit 9' and located below the level of the solutions in the tanks 5 and 6. Connecting the tanks with the mixing chamber are solution communicating means in the form of solution lines 8 and 9 respectively, said solution lines extending into the solution tanks 5 and 6 and terminating at one end in perforated pipe sections 10 and 11 respectively, the other ends of the solution lines extending into the mixing chamber 7 and terminating in solution outlets 12 and 13 respectively, as shown clearly in Figure 1 of the drawings. Each of the tanks is further provided with an additional perforated pipe section, as shown at 14 in Figure 2, such pipe sections being connected to the solution lines by means of by-passes 15. Between the perforated pipe sections and the solution lines are valve structures hereinafter described, these structures being normally closed during nonuse of the apparatus and being adapted to be opened in time of fire to permit the solutions in the tanks to gravitationally flow down into and through the solution lines and into the mixing chamber for commixture therein to produce the fire extinguishing foam.

Means is provided for conducting the generated foam from the mixing chamber to the point of application, namely the fire, such means in the present invention comprising a foam riser 16 extending upwardly from the pit 9' and provided at its upper end with a foam delivery mouth 17 fitted to an oil tank 18 and opening into the said oil tank above the maximum level of the oil therein. The foam generated in the mixing chamber by the admixture of the solutions discharging through the solution outlets 12 and 13 moves up the foam riser, due in part to the difference in specific gravity of the solutions in the tanks and the foam resulting from their admixture, such a system being described and claimed in my co-pending application above referred to, Serial Number 421,634, filed November 4, 1920.

For the purpose of equalizing the pressure on the solutions in the tanks 5 and 6 exerted at the solution outlets 12 and 13, and for other purposes that will become clearer hereinafter means is provided for connecting the foam riser with the solution tanks, such means consisting in an equalizing pressure pipe 19 connecting each of the tanks to the foam riser 16.

For normally preventing the solutions from entering the solution lines, any desired

form of valve may be used, the preferred embodiment of my invention including a valve construction which is not affected by the corrosive action of the chemical solutions used and which is capable of operation at all times. To this end the construction consists of sealed glass disks, here generally designated as 20 and 21, mounted in the line of connection between the perforated pipe sections and the solution lines. These disks normally prevent the entry of the solutions into the solution lines and are adapted in the event of fire to be broken to permit the solutions to enter the solution lines. Similar glass disks are provided as at 22, shown in Figure 2, between the perforated pipe sections 14 and the by-pass 15. Such a valve means has been found to be operable at all times, independent of any period of nonuse of the device.

Means are provided for automatically setting the device into operation in the event of fire, such means consisting in provisions for breaking the glass seal disks upon the occurrence of the fire. In the present form of the invention, such provisions include the plungers 23 mounted for vertical movement in spiders 24, forming part of the acid and basic tanks 5 and 6, these plungers being provided at their lower ends with breaker weights (not shown) for rupturing the glass seal disks, the plungers being provided at their upper ends with heads 25 adapted to be struck by the falling of weights such as ball weights 26 in the event of fire. The weights 26 are both connected to a counter-weight 27 in the oil tank, a cord or chain 28 and a plurality of fusible links 30 being provided for connecting the weights together, this control line being trained to move over a system of pulleys 29 conveniently located in the apparatus as shown in the drawings, and through the equalizing pipe 19 and part of the foam riser 16, these parts thus providing means for completely housing or encasing the control line protecting the same against accidental operation or damage. In the event of fire in the oil tank, the links will be fused, as is obvious, breaking the line of connection between the ball weights and the counter-weight, permitting the weights 26 to fall, actuating the plungers 23 downwardly for the simultaneous breaking of the sealed glass disks 20 and 21, the acid and basic solutions being thereby permitted to simultaneously enter the solution lines and into the mixing chamber for the necessary commixture.

Means is also provided for manually setting the apparatus into activity in the event of the failure of operation of the automatic means, such means including a second set of plungers 31, one in each tank, the plungers being similar in construction and operation to the plungers 23, these plungers be-

ing adapted to be actuated by ball weights 32, shown in Figures 2 and 3 of the drawings, these weights being connected to move in unison similar to the weights 26 and both 5 being connected to a cord or chain 33, movable in guiding means such as pipe section 34, the cord or chain 33 terminating in an eye 34', adapted to be received by a hook 35, mounted in a fire-proof box 36 at a point 10 remote from the fire, as clearly shown in the drawings. In the event of non-operation of the automatic means described, the cord 33 is unhooked and released to permit the weights 32 to drop and actuate the slidable 15 plungers 31 for simultaneous breaking of the glass seal disks 22 to permit the solutions in both the acid and basic tanks to flow into the solution lines through the bypasses 15.

20 One of the features of my invention is to provide a fire extinguishing apparatus of the type herein disclosed which shall not be affected by weather changes, the acid and basic solutions used being affected by cold 25 weather. To provide a non-freezing system the acid and basic tanks 5 and 6 respectively are interred, as shown in the drawings, and the solution lines connected thereto are lead downwardly and into the bottom 30 of the pit 9'. With the parts so arranged, it has been found that the system is not affected by cold weather.

For the purposes of obtaining convenient 35 access to the parts of the apparatus, manheads 37 may be provided in the tanks, a manhead 38 being also provided for convenient access into the mixing chamber 7. A permanent ladder 39 may, if desired, be provided in the pit 9'.

40 The operation of my device will be apparent from the above description thereof. In the event of a fire, the breakable valves 20 and 21 or 22 will be broken either automatically by the occurrence of a fire in the 45 oil tank, or manually by release of the cord 33, the component solutions in the tanks flowing through the solution lines and into the mixing chamber, commixing therein for the production of the fire extinguishing 50 foam. The foam moves up the foam riser to a point elevated substantially with respect to the solution tanks, the operating pressure being provided by the difference in specific 55 gravities between the component solutions and the foam, and also by the pressure exerted on the levels of the solutions in the tanks 5 and 6, a part of the foam in the riser moving through the equalizing pipe section 19 for the production of this pressure. The 60 greater mass of the foam moves up the riser and discharges through the foam delivery mouth into the tank, quickly spreading over the surface of the burning oil therein, rapidly extinguishing the same.

65 From the above it will be apparent that I

have provided a fire fighting unit especially adaptable in oil fields, but which may obviously be used in other locations, and in which the parts are arranged in a simple manner, the parts being so constructed and means being provided whereby a high degree of certainty of operation is obtained, thus yielding a maximum of fire protection for oil fields or the like.

While I have shown my device in the preferred form, it will be obvious that many changes and modifications may be made in the structure disclosed without departing from the spirit of the invention, defined in the following claims.

I claim:

1. In a fire extinguishing apparatus, a plurality of containers for holding component solutions which are adapted to be commixed in the event of fire to produce a fire extinguishing foam, a mixing chamber associated with said containers and located below the levels of the solutions in said containers, ducts connecting the containers with the mixing chamber, means for conducting the foam from the mixing chamber to a foam delivery station situated above the level of the solutions in the containers, and an equalizing pressure means connecting the containers with the conducting means.

2. A non-freezing fire extinguishing system comprising a plurality of interred solution tanks, a mixing chamber located below the level of the solutions in said interred tanks, provisions for commixing the solutions in time of fire to generate the fire extinguishing foam, means for conducting the foam from the mixing chamber to a delivery station above the level of solutions in the tanks, and pressure equalizing means connecting the tanks with the conducting means.

3. In a fire extinguishing device in which component solutions are adapted to be commixed in the event of fire to produce a fire extinguishing foam, tanks for the component solutions, a mixing chamber located below the level of the solutions in the said tanks, means connected to the mixing chamber for conducting the foam generated therein to a delivery station above the level of the solution in the tanks, ducts connecting the tank with the mixing chamber, valve means normally closing said ducts adapted to be opened in time of fire to permit solution flow and solution commixture in the mixing chamber, means for opening the said valve means including a breakable control line, and an equalizing pressure pipe connecting the tanks with the conducting means, the said pipe defining means for encasing the control line.

Signed at New York, in the county of New York and State of New York, this 17th day of December, A. D. 1920.

ORLANDO R. ERWIN.
